VERTICAL DRAFT RELIEF

Louis P. Hine, Jr., Elyria, Ohio, assignor to The C. A. Olsen Mfg. Co., a corporation of Ohio
Filed Dec. 2, 1963, Ser. No. 327,228
10 Claims. (Cl. 126—116)

This invention relates to gas fired appliances such as gas furnaces and concerns particularly vertical draft relief.

An object of the invention is to provide improved, attractive gas fired furnaces, substantially unaffected by downdraft and without excessive back pressure, without producing carbon monoxide.

Conventionally, gas fired furnaces are provided with a draft hood to vent the flue products without altering efficiencies or flame characteristics under varying chimney updraft conditions. The draft hood is also intended under chimney downdraft conditions to vent the downdraft to the extent that it does not disturb flame characteristics and create carbon monoxide.

To accomplish this downdraft venting on a built-in draft hood usually means that a sloping deflector baffle is built directly under the draft hood relief opening that deflects the downdraft out through the front of the furnace so that the burners themselves are not affected by air velocities or flue products. Excessive deflection must be avoided because any great deflection creates a back pressure which slows down the escape of the flue products spoiling combustion and producing carbon monoxide.

However, it has been considered desirable to improve the appearance of a gas fired furnace by the elimination of the opening in the front of the furnace. This necessitates deflecting the downdraft in a different direction. Merely turning the downdraft 180° and discharging through enlarged openings in the horizontal top panel of the furnace tends to result in back pressures becoming so severe inside the draft hood that flames float off burners and carbon monoxide is produced in excessive amounts.

It is accordingly an object of the invention to overcome the foregoing difficulties and to provide reliable, safe draft hoods.

Other and further objects, features and advantages of the invention will become apparent as the description proceeds.

In carrying out the invention in accordance with a preferred form thereof a reshaped draft hood is provided with larger venting areas and means are provided to split the downdraft gradually with a deflector baffle. Back pressure is overcome by providing a modified venturi effect by baffling the inner side of the draft hood.

A better understanding of the invention will be afforded by the following detailed description considered in conjunction with the accompanying drawing in which:

FIG. 1 is a front elevation of a gas fired furnace employing an improved draft hood with vertical draft relief.

FIG. 2 is a view of a vertical section of the furnace of FIG. 1 represented as cut by a central vertical plane.

FIG. 3 is a top view, and

FIG. 4 is a fragmentary view of the furnace and draft hood represented as cut by a vertical plane with a portion of the draft hood broken away to expose the interior.

The invention is illustrated as employed in a sheet metal, gas fired furnace having a front wall 11, side walls 12 and

2

a horizontal top panel 13 forming the upper portion of a bonnet through which a vertical vent or flue pipe 14 extends.

The front wall 11 of the furnace is continuous and without any openings except for an opening 15 to receive gas supply pipes (not shown) and provide access to a conventional burner or burners 16 which extend through openings 17 in a fire box wall 18. There is a flue-product inlet 19 at the upper portion of the fire box wall 18.

Within the furnace bonnet there is a draft hood 21, also preferably composed of sheet metal. The draft hood 21 is substantially in the form of a flat-sided box shown as trapezoidal, formed of joined walls including a top wall 22, side walls 23, a front wall 24, a back wall 25 and a bottom wall 26. Although the invention does not exclude a rectangular construction the side walls 23 are shown as slanting inward toward the front of the furnace. In the construction illustrated the back wall 25 of the draft hood 21 is secured against the fire box wall 18 although it may be a continuation or form a part of the fire box wall 18. The flue product inlet 19 constitutes an opening in the back wall 25 of the draft hood 21.

The draft hood top wall 22 has a flue pipe opening or vent opening 27, and is preferably formed with a flange 28 around the edges of the opening 27 to form a nipple for connection to the flue pipe 14 which passes through the top panel 13 of the furnace and terminates at the top wall 22 of the draft hood 21, said top wall being spaced from the upper horizontal panel 13 of the furnace. The front wall 24 and the side walls 23 are continuous.

The bottom wall 26 has a draft relief opening 29 which is larger than the flue pipe opening 27. Although the invention is not limited thereto, for the sake of illustration the flue pipe 14 has been represented as being circular in cross section but the openings 27 and 29 are shown as rectangular. The opening 29 is larger than the opening 27 to guard against creating excessive back pressure in the event of downdraft through the flue pipe 14. In addition the downdraft is split gradually by providing a deflector baffle 31. In order to provide still further assurance of overcoming back pressure a modified venturi effect is provided by baffling the inner side of the draft hood by means of a venturi baffle 32 extending upward from the bottom wall 26 of the draft hood 21.

The deflector baffle 31 is shown as composed of sheet metal extending horizontally further than the bottom wall 26 of the draft hood 21, preferably having a rising center 33 and upwardly slanted ends or edges 34. The venturi baffle 32 is shown as composed of straight vertical side walls 35 extending from front to rear between the front wall 24 and the rear wall 25 of the draft hood 21. The venturi baffle side walls 35 may be joined to the bottom wall 26 at the sides of the opening 29 therein. If desired, as shown, the vertical walls 35 of the venturi baffle 32 may be bent up from the same sheets of metal forming the bottom wall 26.

Preferably a greater venturi effect is accomplished by flaring the upper edges 36 of the vertical walls 35 of the venturi baffle 32 and also the edge 37 of the opening 19 in the back wall 25 to form a throat.

The rising center portion 33 of the deflector baffle 31 is centered with respect to the venturi baffle 32. Enlarged openings 38 and 39 are provided at each side on the right

and left ends of the horizontal top panel 13 of the furnace for vertical draft relief. The center rising portion 33 of the deflector baffle 31 is a ridge in the shape of an inverted V channel comprising upwardly bent slanting portions 41 and 42 of the sheet material of which the deflector baffle 31 is formed; and the deflector baffle 31 extends in the direction from front to rear between the furnace front panel 11 and the fire box vertical wall 18 so that no upwardly sloping edges are required at the front and rear ends of the deflector baffle 31.

Referring to FIG. 2 of the drawing it will be apparent that the products of combustion of the burners 16 constituting the flue products rise and enter the opening 19 in the draft hood 21, normally continuing upward through the flue pipe 14. Varying updraft conditions in the chimney to which the flue pipe 14 is connected do not alter efficiencies or flame characteristics of the burners 16 since the flue products are vented to the draft hood 21 which is substantially larger in horizontal cross sectional area than the flue pipe 14.

In the event of downdraft through the chimney and the flue pipe 14, the flue products in the flue pipe 14 do not disturb the flames of the burners 16 since they are vented downward through the throat of the venturi baffle 32, through the opening 29. Thereafter they are split by the sloping walls 41 and 42 of the center rise portion 33 of the deflector baffle 31, then diverted upward by the upwardly sloping ends 34 of the deflector baffle 31 to escape through the enlarged openings 38 and 39 in the horizontal top panel 13 of the furnace.

The downdraft path through the flue pipe 14 is represented by the arrows 40 and, in case of chimney downdraft, the downdraft path of the flue products from the flue product opening 19 is in the direction of the arrows 43. Creation of back pressure is avoided by the ample size of the venturi throat in the venturi baffle 32 so that the combined flue products follow the paths of curved arrows 44 downward against the deflector baffle 31 thence along arrows 45 and upward in the direction of arrows 46. As soon as the downdraft stops, of course, the flue products resume their usual path upward from the burner 16 through the opening 19 and directly upward through the flue pipe 14.

While the invention has been described as embodied in concrete form and as operating in a specific manner in accordance with the provisions of the patent statutes, it should be understood that the invention is not limited thereto, since various modifications will suggest themselves to those skilled in the art without departing from the spirit of the invention.

What is claimed is:

1. In a gas fired furnace a draft hood therefor, and a furnace bonnet with a substantially horizontal wall at the top with a flue pipe opening therein and draft relief openings on either side thereof, and a flue pipe extending through said flue pipe opening terminated below said bonnet top wall, said draft hood comprising:

- (a) a top wall with an opening therein connected to said flue pipe,
- (b) vertical front and side walls,
- (c) a vertical rear wall with a flue product opening therein,
- (d) a bottom wall with a relief opening therein larger than the flue pipe opening in the top wall, and
- (e) a horizontally extending deflector baffle spaced from and below the bottom wall.

2. A draft hood as in claim 1 wherein the deflector baffle comprises sheet material larger than said bottom wall with upward slanting outer edges and a raised center narrower than the relief opening in the bottom wall.

3. In a gas fired furnace, a draft hood therefor and a furnace bonnet with a substantially horizontal wall at the

top with a flue pipe opening therein with draft relief openings on either side thereof, a flue pipe extending through said flue pipe opening terminating below said bonnet top wall, said draft hood comprising in combination:

- 5 (a) a top wall with an opening therein provided with a flange connected to said flue pipe,
- (b) vertical front and side walls,
- (c) a vertical rear wall with a flue-product opening located approximately in the upper half thereof,
- (d) a bottom wall with a relief opening therein,
- (e) an internal venturi baffle connected to said relief opening and extending substantially vertically from the bottom wall with outwardly flaring upper edges, and
- (f) a horizontally extending deflector baffle spaced from and below the bottom wall.

4. In a gas fired furnace:

- (a) a furnace bonnet with a substantially horizontal wall at the top with a flue pipe opening therein and draft relief openings on either side thereof,
- (b) a flue pipe extending through said flue pipe opening terminating below said bonnet top wall, and
- (c) a draft hood comprising:

- 20 (1) a top wall spaced from said furnace bonnet top wall with an opening therein connected to said flue pipe,
- (2) vertical front and side walls,
- (3) a vertical rear wall with a flue product opening therein,
- (4) a bottom wall with a relief opening therein, and
- (5) means for deflecting flue products issuing from said bottom-wall relief opening upward toward said draft relief openings in the furnace bonnet.

5. The combination of claim 4 wherein the draft hood includes an internal venturi baffle connected to said bottom wall relief opening and extending upward from said bottom wall.

6. In a gas fired furnace a draft hood therefor, and a furnace bonnet with a substantially horizontal wall at the top with a flue pipe opening therein and draft relief openings on either side, and a flue pipe extending through said flue pipe opening terminating below said bonnet top wall, said draft hood comprising in combination:

- (a) a top wall with an opening therein connected to said flue pipe,
- (b) vertical side walls,
- (c) a vertical rear wall with a flue product opening located approximately in the upper half thereof,
- (d) a bottom wall with relief opening therein,
- (e) an internal baffle connected to said relief opening and extending upwardly from the bottom wall, and
- (f) means for deflecting upwardly any flue products issuing from said relief opening.

7. A draft hood as in claim 6 in which the deflecting means constitutes a horizontally extending deflector baffle spaced from and below the bottom wall.

8. A draft hood as in claim 7 wherein the deflector baffle comprises sheet material larger than said bottom wall with a central upwardly directed inverted V-channel formed therein.

9. In a gas fired furnace:

- 65 (a) a furnace bonnet with a substantially horizontal wall at the top with a flue pipe opening therein and draft relief openings on either side thereof,
  - (b) a flue pipe extending through said flue pipe opening terminating below said bonnet top wall, and
  - (c) a draft hood comprising:
- (1) a top wall spaced from said furnace bonnet top wall with an opening therein connected to said flue pipe,
  - (2) vertical front and side walls,

- (3) a vertical rear wall with a flue product opening therein,
  - (4) a bottom wall with a relief opening therein,
  - (5) an internal venturi baffle connected to said bottom wall relief opening and extending upward from said bottom wall, and
  - (d) a deflector baffle spaced from and below the bottom wall of said draft hood and extending beyond the draft hood to divert any flue products issuing from said bottom wall relief opening upward toward said draft relief openings in the furnace bonnet.
10. The combination of claim 9 wherein the deflector baffle comprises sheet material with a center ridge extending the length of the baffle and upturned ends extending the length of the baffle.
